Morton Davis, South Orange, N. J., assignor to
Joseph Davis Plastics Co., Arlington, N. J., a
corporation of New Jersey

Application February 15, 1947, Serial No. 136,930

Term of patent 14 years

(Cl. D83—1)

To all whom it may concern:

Be it known that I, Morton Davis, a citizen of the United States, residing in South Orange, county of Essex, and State of New Jersey, have invented a new, original, and ornamental Design for a Combined Handle and Teething Ring or Similar Article, of which the following is a specification, reference being had to the accompanying drawing, forming a part thereof.

Fig. 1 is a front elevational view of a combined handle and teething ring embodying my new design.

Fig. 2 is a vertical, sectional view thereof, taken on line 2—2 of Fig. 1, and

Fig. 3 is an enlarged, horizontal, sectional view thereof, taken on line 3—3 of Fig. 1.

I claim:

The ornamental design for a combined handle and teething ring or similar article, as shown.

MORTON DAVIS.
